TAG PRINTING DEVICE

Herman I. Lippard, Lansdowne, Pa.

Application August 29, 1933, Serial No. 687,258

9 Claims. (Cl. 101—93)

The present invention relates to tag or ticket printing devices.

The main object of the invention is to provide a tag or ticket printing device of relatively simple, inexpensive and rugged construction, which permits speedy change of type set-up and which is capable of being operated with facility by persons having very little experience.

Another object is to provide such a device which is capable of printing one or more characters in one or more lines on a relatively small tag or ticket.

Another object is to provide such a device which is capable of being readily adjusted to print two or more lines of type very closely together or further apart as may be desired.

Still another object is to provide such a device of relatively light weight compared to the types of printing devices now on the market and the parts of which can be readily and inexpensively replaced with standard parts by persons having comparatively little mechanical ability.

In one of its broad aspects, the device of the invention comprises a base upon which are mounted for reciprocation toward and away from the printing surface one or more type-carrying plates. The plates may advantageously be of substantially flat form disposed with their planes substantially perpendicular to the printing surface and carrying a line of changeable characters on their lower ends, said line of characters constituting the printing type. The plates are preferably pivoted about a horizontal axis through their planes so that their lower ends may be brought closely together, thus permitting very close spacing of the lines of type. The plates may also be pivoted about a horizontal axis perpendicular to their planes so that they may be swung away from the base to facilitate changing of the type.

The inventive concept involved is capable of receiving a variety of mechanical expressions one of which, for the purpose of illustrating the invention, is shown in the accompanying drawings, wherein:—

Figure 1 is a perspective view showing the device positioned on a suitable support, part being broken away at several places to show details of construction and one of the type-carrying plates being shown in non-operative position by means of dot and dash lines;

Figure 2 is an end view in elevation, the various possible movements of the type-carrying plates being shown in dot and dash lines;

Figure 3 is a detail view showing the manner in which the strip of type is connected to the endless cord;

Figure 3a is a detail view, partly broken away, showing an alternative way of connecting the strip of type to the cord;

Figure 4 is a detail view showing a form of finger-hold which may be used in connection with the device;

Figure 5 is a detail view showing an alternative way of attaching the finger-hold of Figure 4 to the endless cord;

Figure 6 is a detail view of an alternative form of finger-hold;

Figure 7 is a cross-sectional view taken along line 7—7 of Figure 2;

Figure 8 is a detail view showing the manner of pivotally mounting the type-carrying plate to the housing; and

Figure 9 is a view of one of the duplicate faces of an alternative form of type-carrying plate.

Referring in greater detail to Figure 1, the reference character T designates a table top or other suitable support for the device and Tg denotes a tag or ticket in position to be printed upon. The tag or ticket may be of the conventional form of price tag and need not be described in detail.

For the purpose of ready reference and convenience of description, the description of the device will center about the following elements which may be termed elements of reference; namely, the base portion 1, the housing 2, the type-carrying plates 3, 3 and the actuating means 4.

The base portion 1 is shown as having the general form of an inverted U, the legs of which are designated as 5, 5 and the connecting or yoke portion as 6. The legs 5, 5 may each be formed with the forwardly extending feet 7, 7. The feet 7, 7 not only serve to impart greater stability to the device especially when in use but may also be used as a mechanical aid in properly alining the ticket Tg with the printing elements of the device.

Pivotedly mounted between the legs 5, 5 of the base by means of the fixed transverse rod 8 is the inking pad 9 which may be of conventional form. The pad may be normally maintained with its upper or inking surface 10 against the face of the type by any suitable means. In Figure 2 of the drawings I have shown the pad connected at the point 11 to the link 12 which in turn is pivotally connected at its opposite end 55

13 to the angle bar 14 which is secured in any suitable manner to the housing 2. When the housing 2 is in the position shown by solid lines in Figure 2, the pad is maintained with its upper 5 or inking surface against the type. When the housing 2, as will hereafter be pointed out, moves to its lowermost position shown in dotted lines in the same figure, the connecting link 12 causes the pad to swing out of the way of the type as indicated in dotted lines.

The reference numeral 15 denotes a second inverted U-shaped element which, as shown in Figures 1 and 7, is normally nested within the upper portion of the base member 1. The member 15 has the two relatively short legs 16, 16 connected by the yoke portion 17. The inner surfaces of the legs 5, 5 of the base member 1 and the outer surfaces of the legs 16, 16 of the member 15 are provided with cooperating elements to permit the member 15 to slide or reciprocate between the legs of the base member. As shown in Figures 1 and 7, the cooperating elements may take the form of a groove 18 in the inner surface of each of the legs 5, 5 and one 25 or more projections or pins 19 on the outer surface of the legs 16, 16. The grooves 18, 18 provide a pair of tracks within the base portion 1 upon which the U-shaped member 15 may be reciprocated when the device is actuated in the 30 manner to be hereinafter pointed out.

The housing 2 as shown in Figures 1 and 2 is secured to the yoke portion 17 of the element 15 by means of the connecting element 20 which may advantageously be formed integrally with 35 the yoke portion 17. The housing 2 is substantially U-shaped in horizontal cross-section and has the two side walls 21, 22, connected together by the end wall 23. The end wall 23 is shown as being provided with the horizontal slot 24 for 40 a purpose to be hereinafter pointed out.

Each of the type-carrying plates 3 is of identical construction and consists of an upper substantially rectangular portion 25 and a lower substantially rectangular portion 26 of less width. 45 Secured in any suitable manner to each side of the upper end of the portion 25 is a metallic strip 27, each of which strips extends a short distance above the upper end of the portion 25. The upper end of the portion 25 and the upper 50 edge of each of the metallic strips 27 are provided with the series of rectangular notches 28 forming the series of teeth 29.

Mounted on the upper end of the type-carrying plate and clamped between the metallic strips 27 55 in the plane of the plate 3 is a fixed shaft 30. Mounted on this shaft in each of the notches 28 is a small pulley 31.

One corner of the lower end of the portion 25 of the plate 3 (see Figure 8) is provided with a 60 cut-out 32. Secured to each side of the lower end of the portion 25 is a metallic strip or side plate 33. These strips extend over the cut-out 32 and are provided with the lugs 34. The lugs and the cut-out form a bifurcated ear, which 65 as will hereinafter be pointed out serves to pivotally connect the plate 3 to the housing 2.

The reference numeral 35 designates a series of endless type-carrying cords, each of which passes completely about both faces and the ends 70 of the type-carrying plate 3. The cords are trained about the pulleys 31 and for the length of the broader or upper portion 25 of the plate 3 are maintained in spaced-apart parallel relation by means of the second set of pulleys 36. 75 A third set of pulleys 37 serves to bring and

maintain the cords 35 into closer parallel relation for the entire length of the lower or narrower portion 26 of the plate 3. It is to be understood that both faces of the plate 3 are provided with the sets of pulleys 36 and 37. The 5 pulleys 36 and 37 are disposed with their axes at right angles to the plate 3.

Each one of the cords 35 carries a flexible strip 38 (preferably of rubber) bearing raised characters which may take the form of letters, 10 numerals and symbols such as are indicated by the reference numeral 39. In Figures 3 and 3a are illustrated two of the many possible ways of connecting the strip of type 38 to the cord 35. In Figure 3 the end of the strip 38 is shown 15 folded about the end of the cord 35 and a clamp 40 of flexible metal clamping the two together. The clamp may be similar to the conventional type of shoe lace tip. In Figure 3a the flexible strip 38 is shown secured to the clamp 40a by 20 means of crimping or in other suitable manner and the end of the cord 35 threaded through an aperture 40b of the clamp and knotted as at 40c. The described manner of connecting the cords 35 and the strips 38 renders it a very simple 25 matter to replace the strips 38 whenever deemed necessary or desirable.

The reference numerals 41 and 41' designate two alternative forms of finger holds for moving the cords 35 for the purpose to be hereinafter 30 pointed out. The finger hold 41 is a cylindrical piece of metal or other suitable material having a central bore and a series of connecting circular recesses 42. Figures 4 and 5 illustrate two alternative ways of connecting the finger hold 41 35 to the cord 35. In Figure 5 the cord 35 is shown as passing entirely through the bore of the element 41 and being secured to said element by engagement between a knot 43 formed in the cord and one of the recesses 42 in the element. In 40 Figure 4 the cord 35 is shown as having the two free juxtaposed ends, both of which ends are provided with the knots 44 which engage in the recesses 42 in the element 41.

The alternative form of finger hold shown in 45 Figure 6 is a cylindrical element 41' having a bore 45 and one or more threaded or tapped holes 46 at right angles to the bore to receive the set screws 47. The cord 35 passes through the bore 45 and is clamped against the threaded hole as 50 at 48 by means of the set screw 47. The knots 49 may be used instead of the finger holds 41 and 41' to move the cords 35.

It will be understood from the foregoing description that the line of type on the bottom 55 end of the plate 3 constitutes the active or printing type when the device is actuated. As has been previously pointed out, the inking surface 10 of the inking pad 9 is normally pressed against the printing type until it is pushed out of the 60 way by the actuation of the device. By means of the finger holds 41 it is possible to bring any desired arrangement or combination of letters, numerals and symbols to the bottom of the plate. In order to facilitate the printing operation, the 65 cords should be taut. For this reason, the cords should be made of a material having a very small stretch. The manner of connecting the cord 35 to the finger hold 41 shown in Figure 4 renders it a simple matter to keep the cords 35 70 taut. If the cord loses some of its tautness, it is only necessary to move the knots 44 to recesses 42 which are closer together. The same function is possible in the modification shown in Figure 6.

In order to maintain the type properly aligned and to enable several lines of type to be printed closely together, I may provide the device with the clamping means now to be described. The 5 clamping means consists of two duplicate members 51, 54 in the form of metallic strips hingedly connected together and to one edge 52 of the lower end of the plate 3. Each of the strips 51 is provided with a bent end portion 53 having an 10 aperture 54 to receive one of the pins 55 and 56 of the locking element 57. It will be understood that the length of each of the bent ends 53 is about half of the thickness of the plate 3. The locking element 57 is pivotally connected at 58 15 to the plate 3 by means of its bifurcated end 59. The slot 60 adjacent the lower end of the plate 3 serves to facilitate the clamping action of the clamping means. Each of the strips 51 and the lower edge of the slot 60 grip the type-bearing 20 strips 38 between them, a portion of each of the strips 38 being forced into the slot. In this way the thickness of the clamped portion of the type-bearing strips 38 is reduced to a minimum, thus making it possible to space the lines of printing 25 very closely together.

Reference will now be made to Figure 8, wherein is illustrated the manner in which each of the type-carrying plates 3 is pivotally mounted on the end wall 23 of the housing 2. As shown in said 30 figure, the plate 3 is pivotally connected to the element 61 which in turn is detachably connected to the end wall 23. The element 61 has a flat body portion 62 which is parallel to the end wall 23 and terminates at its upper end in the outwardly extending lug or ear 63 and at its lower end in the inwardly extending bifurcated portion 64. The lug 63 is received in the bifurcated ear 35 of the plate 3 which has been described as being formed by the cut-out portion 32 and the lugs 34 40 and is pivoted therefrom at 65 by means of a pin or rivet. The element 61 is detachably connected to the end wall 23 of the housing at a point intermediate its ends by means of the screw 66 and the washer plate 67. The screw passes 45 through the washer plate, the aperture 24 in the end wall 23 and the body portion 62 of the element 61 and may be provided near its threaded end with a nut (not shown). The washer plate 67 is shown provided with the struck-in portions 50 68 which engage in the slot 24 to keep the washer plate from rotating. The bifurcated lower end 64 of the element 61 as shown in Figure 1 extends inwardly below the lower end of the end wall 23 for a purpose to be pointed out.

55 From the foregoing description it is thought to be clear that each of the type-carrying plates 3 may be swung about the pivot 65 to a position inside or outside of the housing 2. In Figure 1, one of the plates 3 is shown in its position within 60 the housing in solid lines and in its position outside the housing in dot and dash lines. It is to be noted that when inside the housing, the broad portion 25 of the plate 3 is disposed upwardly while in its outside position the narrow portion 65 26 is disposed upwardly. Also, that in its inside position the narrow portion 26 fits in between the forks of the bifurcated end 64 of the element 61. One edge of the narrow portion 26 is provided with a notch 69 to accommodate the head of the screw 66 and the washer 67 when the plate 3 70 is in its position within the housing. The opposite edge is provided with a notch 69a which cooperates with the pivoted member 70 of a locking device to maintain the plate 3 in upright position 75 within the housing 2. The member 70 is pivoted

to the inner side wall 22 of the housing at 72 for movement in a horizontal plane and is received within the notch 69a and under the pin 71 which is fixed to an edge of the outer side wall 21.

The lower or narrow portion 26 of the type-carrying plate 3 may be long enough to provide for strips 38 carrying a full complement of characters. However, to avoid excessive height of the plates 3 in case a great number of characters are used, the alternative form of plate 3' shown in 10 Figure 9 may be substituted for one or more of the plates 3. The plate 3' is substantially rectangular at its upper end and is bifurcated at its lower end by the slot 80. The two bifurcations are designated by the numerals 81 and 82. 15 It is to be noted that the fork 81 is approximately twice as wide as fork 82 but is somewhat shorter. The lower end of the fork 82 may advantageously be disposed at an obtuse angle with 20 its outer edge.

The structure of both faces of the plate 3' is identical and hence only one face need be described, it being understood that each of the details now to be described is duplicated for each side. The reference character 83 denotes a pulley-carrying plate of substantially triangular shape, the sides being designated in order of their length by the numerals 84, 85 and 86. The longest side 84 is substantially superposed along the upper end of the plate 3' and the apex of the triangle is substantially in a straight line above the slot 80. The side 85 of the triangle is disposed to the side of the plate 3' corresponding to the wide bifurcation 81 while the shortest side 86 is disposed to the side corresponding to 35 the narrow bifurcation 82. Along the side 85 is spaced the series of pulleys 87 and along the side 86 is spaced the series of pulleys 88, the number of pulleys in the two series being equal.

Along the lower end of the bifurcation 81 is secured the strip 89 having the notches 90 which are equal in number to the pulleys in each of the sets 87 and 88. In each of the notches is mounted a pulley 91 with its axis in the plane 3'. Each pulley 91 is mounted on a separate horizontal 45 shaft 91a. The bifurcation 82 is shown provided with the slot 92. Passing over each of the pulleys 91 about the lower end of the bifurcation 81, over the corresponding pulley of each of the sets 87 and 88 and about the lower end of the bifurcation 82 is an endless cord 93 carrying a strip of type 94. The lower end of the bifurcation 82 may be provided with the teeth or serrations 94a to separate the type-bearing strips 94. The structure of the cords 93, the strips of type 94 55 and the finger holds 95 may be the same as that of the corresponding elements of the previously described plate 3. The pulleys 87 and 91 maintain the endless cords 93 in wide parallel relation while the pulleys 88 and the serrations 94a 60 maintain the cords in close parallel spaced relation. The fact that each of the cords passes up one side and down the other of both faces of the plate 3' greatly increases the character-carrying capacity of the plate without rendering it necessary to unduly increase the height of the plate. 65

In Figure 9 I have illustrated a modified form of clamp for holding the type-carrying strips 94. The clamp consists of the two hinged metallic strips 96 and the locking element 97 which is 70 shown pivoted intermediate its ends to the inner edge of the bifurcation 82. The hinged strips 96 and the locking element 97 may be provided with cooperating elements (not shown) such as the apertures 54 and pins 55, 56 of the clamp shown 75

in Figure 1. The plate 3' may be also provided with the bifurcated ear 98 for pivotally mounting the plate on the housing 2. It is thought to be obvious from the foregoing description that the 5 plate 3' may be swung to a position within the housing or to a position outside the housing in the same manner as can plate 3.

The device of the invention may be either hand or machine operated. For convenience of illustration, the device is shown as being hand-actuated. The actuating means is indicated generally by the reference numeral 4. The numeral 100 denotes a handle which is connected to the yoke 17 of the inverted U-shaped member 15 10 by means of a hollow shaft 101. The hollow shaft is connected to the yoke 17 in the following manner:—The lower end of the shaft is supported on the yoke 17 in register with a central aperture 102. A short threaded rod 103 is threadably engaged with the lower end of the hollow shaft 101 and extends down through the aperture 102. A nut 103a serves to complete the connection.

As shown in Figure 7 the yoke 6 of the base member 1 is provided with a central hub 104 through which the shaft 101 reciprocates when actuated. The shaft 101 is provided with two oppositely disposed vertical slots 105. Resting in a recess 106 on the hub 104 and passing through the two slots 105 of the hollow shaft is a pin 107. 20 Housed within the hollow shaft and resting upon the pin 107 is a coiled spring 108. To reinforce the shaft 101 and to impart greater ruggedness and stability to the device, the shaft 101 may be connected directly to the housing 2 by means of 25 the angular member 109.

The operation of the device may be briefly summarized as follows: The device is placed on a flat surface (see Figure 1), the housing 2 is unlocked by swinging the pivoted member 70 to one side 40 and the type-carrying plates 3 are turned about the pivot 65 to bring them into the position indicated by the dot and dash lines. This brings the printing edge of the plate into full view and renders possible accurate setting of the type. Due 45 to the construction of the device, this operation does not in any way affect its stability. The clamping strips 51, 51 are then unlocked as shown by dot and dash lines and any desired arrangement or combination of characters, letters, figures, etc. 50 brought to the printing end of the plates 3 by means of the finger holds 41 or 41' or knot 49. In practice it has been found preferable to use both hands in moving the type, one hand manipulating a finger hold or knot on one side of the plate and the other hand manipulating a knot or 55 finger hold on the other side of the plate. The clamping strips 51, 51 are then locked, the plates 3 swung back into the housing 2 and the housing locked by means of the pivoted member 70. One 60 of the plates 3 may be brought into accessible position at a time in order to facilitate the setting of the type.

A tag or ticket is placed in position and the handle 100 of the device pressed down against the 65 tension of the spring 108. This operation forces the ink pad 9 out of the way and presses the type against the printing surface or tag Tg. When the handle is released, the tension of the spring 108 causes the handle to return to normal position 70 and the inking surface of the pad to be pressed into contact with the type, thus inking the type for the next printing operation.

It is to be noted that the connection of the plates 3 to the housing 2 enables the plates to be moved closer together, if desired, and also renders

it possible to turn the plates so as to bring their lower ends in close proximity. This makes it possible to print the lines very closely together without bringing the body of the plates so close as to interfere with their swinging movement 5 about the pivot 65.

It is within the purview of my invention to construct the plate or plates 3 or 3' with or without the housing 2 as a unit separate and apart from the specific forms of base 1 and actuating means 10 4 which have been illustrated. The unit comprising the plate or plates with or without the housing may be sold for attachment to a suitable form of base to complete the general combination of the foregoing specification. 15

I claim:—

1. In a tag printing device, the combination of a base, a housing mounted on said base for reciprocation to and away from the printing surface, a type-carrying plate of flat form pivotally mounted on the housing so that it may be swung in and out of the housing and having one end parallel to the printing surface, a line of changeable type carried by said end of the plate and means to reciprocate the housing to bring said 25 line of type into contact with the printing surface.

2. As an element of a tag printing device, a type-carrying plate of flat form, a series of spaced endless bands passing about and over a portion of one end of said plate, around both faces and 30 about and over the remaining portion of the said end, the portion of the endless bands passing over the remaining portion of the said end carrying a series of characters.

3. As an element of a tag printing device, a 35 type-carrying plate of flat form, said plate having a wide upper portion and a narrow lower portion, a series of endless bands passing over and around both ends of said plate and being widely spaced for the length of the wide portion of the plate and 40 closely spaced for the narrow portion of said plate, the portions of the bands which pass over and around the narrow portion of the plate carrying a series of characters and the line of characters carried by the lower end of said plate constituting the printing type.

4. As an element of a tag printing device, a strip of flexible material bearing spaced characters, a cord and means connecting said cord and strip, said means consisting of clamp permanently secured to the strip and detachably connected to the cord. 50

5. In a tag printing device, the combination of a base, a flat plate, means for mounting said plate on said base so that it can be reciprocated 55 to and away from a printing surface with its plane perpendicular to the printing surface, means for mounting said plate on said base so that it can be swung to and away from its perpendicular relationship to the printing surface, 60 a line of type carried by the lower end of said plate and means to reciprocate the plate to bring said end into contact with the printing surface to produce a line of printing on said surface.

6. In a tag printing device, a base, a plurality 65 of flat plates mounted on said base, one or more of said plates being mounted for movement parallel to each other and each plate presenting an end to the printing surface, a line of type on each of said ends and means to bring said ends 70 against the printing surface to produce lines of printing thereon.

7. In a tag printing device, a base, a plurality 75 of flat plates mounted on said base and each presenting an end to the printing surface, a line

5 of type on each of said ends, one or more of said plates being pivotally mounted about an axis parallel to the end carrying the type, whereby the ends may be brought into close juxtaposition, and means to bring said ends against the printing surface to produce lines of printing thereon.

10 8. In a tag printing device, a base, a plurality of flat plates mounted on said base and each presenting an end to the printing surface, a line of type on each of said ends, one or more of said plates being pivotally mounted about an axis perpendicular to its plane, whereby said plate or plates may be swung away from said base, and means to bring the ends of the flat plates carrying the type

against the printing surface to produce lines of printing thereon.

9. In a tag printing device, a base, a plurality of flat plates mounted on said base and each presenting an end to the printing surface, a line 5 of type on each of said ends, one or more of said plates being pivotally mounted about an axis parallel to the end carrying the type and one or more of said plates being pivotally mounted about an axis perpendicular to its plane, and means to bring the ends of the flat plates carrying the type 10 against the printing surface to produce lines of printing thereon.

HERMAN I. LIPPARD.
